A. L. ROEBUCK

BOX SECURING MEANS

Filed Jan. 23, 1925

Inventor:
Alfred L. Roebuck
By Wallace L. Lane

UNITED STATES PATENT OFFICE.

ALFRED L. ROEBUCK, OF WINCHENDON, MASSACHUSETTS, ASSIGNOR TO GENERAL BOX COMPANY, OF CHICAGO, ILLINOIS, A CORPORATION OF DELAWARE.

BOX-SECURING MEANS.

Application filed January 23, 1925. Serial No. 4,165.

This invention relates to improvements in box securing means, and has for its object to provide means permitting the reuse of wire bound boxes or other receptacles reinforced or bound with wire, and to provide a splice or tying means for such boxes which may be used with the free ends of the wires of such a box or receptacle.

This and other objects will be more fully described and set forth in the following specification and shown in the accompanying drawings, in which

Fig. 1 is a perspective of a wire bound box to which my securing means has been applied showing the various operations.

Fig. 2 is a side elevation showing the method of attachment of the splice or tying member to one end of one of the box wires.

Fig. 3 is a perspective of one form of splice member.

Fig. 4 is a side elevation of a modified form of splice member, showing its attachment to one end of a box wire.

Fig. 5 is a vertical section along the line 5—5 of Fig. 4.

Fig. 6 is a perspective view of the tying member shown in Fig. 4.

Like numerals refer to like elements in the figures of the drawing, in which 10 indicates generally a form of wire bound box, provided with the box wires 11, extending around the sides of the box, and secured thereto by spaced staples 12, in well known manner.

With wire bound boxes, it is customary to pack the same, after which the cover 10^a is hingedly moved by means of the wiring arrangement to closed position as shown in Fig. 1, and as is well known, the projecting ends of the box wires are of sufficient length to permit their tying together, as indicated by A at the left hand side of Fig. 1.

When it is desired to unpack the box, the wires may be cut at one side edge of the cover, and the cover hingedly moved to open position. It is impractical to uncoil the tied ends of the box wires to permit unhinging, and obviously, when the wires are cut in the manner described, it is impossible to retie the wires as originally done, hence the box is of little or no value for further shipment.

In Fig. 3 I have illustrated one form of a splice or tie member 15 provided with the head 15^a formed by helically coiling a portion of the wire in the manner shown with

one loop 15^b of reduced diameter to form an eye 15^c, the stem 15^d of the tie extending for a considerable distance, as shown in the drawing.

In the use of this form of tie, a free end 12^a of a box wire is inserted through the center of the head 15^a, to project some distance beyond and parallel to the stem 15^d. A portion of the thus extended portion of box wire 12 is then looped or doubled back 65 so that the end 12^a lies parallel to the adjacent portion of the box wire 12 in the manner shown in Fig. 2, after which the tie member 15 is moved outwardly along the wire 12 toward its looped end and the latter is 70 passed through the eye 15^c as shown in Fig. 2. The portion of the end 12^a projecting through and beyond the head 15^a may then be bent or forced outwardly, as indicated in dotted lines in Fig. 2, or over the opposite 75 side of the head 15^a to prevent further relative movement of the tie member 15, with respect to the box wire 12. The stem 15^d is now bent outwardly into engagement with the opposite free end of the same box wire, 80 and the ends are tied or twisted as indicated by B in Fig. 1. This is so accomplished as to place the tie member 15 and the associated box wire 12 under sufficient tension to maintain the box cover in closed position, and to 85 prevent any unlocking of the connection between the head 15^a of the tie member and the end 12^a of the box wire.

In Figs. 4, 5 and 6 I have illustrated a modified form of tie member 20, which is 90 provided with a pair of projecting stems 20^a and 20^b, and a head 20^c formed by helically coiling a portion of the tie member. In this form a pair of eyes 20^d and 20^e are provided as shown particularly in Fig. 5. 95

In the use of this modified form of tie member, projecting end 12^a of the box wire 12 is inserted through the eye 20^c and looped back in the manner previously described, after which the tie member is moved to pass 100 the looped end 12^a through the other eye 20^d and bent to lock the box wire and tie member together, as described in connection with the first embodiment, and as shown in dotted lines in Fig. 4.

With the embodiment just described after attachment of the head 20^c to one end of the box wire 12, either the stem 20^a or the stem 20^b may be attached by twisting or the like to the opposite end of the box wire 110

in the manner described above. The unused stem portion may be tucked or inserted beneath the cover and used for a second tying operation when the box has been 5 opened.

If, as sometimes happens in cutting off the twisted ends of the box wire in first opening the box, little or no projecting wire is left for attachment to the tie member, one 10 of the staples 13 may be removed to provide additional free wire for twisting with the tie member.

In the use of wire bound boxes, I may supply tie members to the shippers or consignees, or in general to purchasers or users 15 of the boxes to permit the reuse of the boxes as desired.

Occasionally the box wires break in the first use of a wire bound box, in which 20 event my tie members may be utilized, thus permitting the boxes, which might otherwise be impaired in value to be used. It should also be noted that the more tension to which the tie member is subjected in 25 fastening a box cover, the more secure is the interlock of the head with the associated box wire end.

It will be obvious that my invention is susceptible of modification, and I do not 30 wish to be restricted to the forms shown and described, except as defined in the appended claims.

What I claim is:

1. A tie device for connecting the free 35 ends of a binding wire for containers, comprising a bent portion forming a head providing a space therein, an end portion of said head being bent to extend across said

space, and a free end portion extending from said first mentioned bent end portion and adapted to be connected to one of said free ends of the binding wire, the other free end of the binding wire being adapted to pass through said space and be bent around said first mentioned bent end portion. 40

2. A tie device for connecting the free ends of a binding wire for containers, comprising a helical portion having an open end, a bent portion at one end of said helical portion and extending across said open end to divide the opening into a pair of eyes, and a portion extending from said bent portion and adapted to be connected to one of the free ends of the binding wire, the other free end of the binding wire being adapted to extend through said helical portion and through said eyes to be looped over said bent portion. 50

3. A tie device for connecting the free ends of a binding wire for containers, comprising a bent portion forming a head providing a space therein, an end portion of said head being bent to extend across said space, and a free end portion extending from said first mentioned bent end portion and adapted to be connected to one of said free ends of the binding wire, the other free end of the binding wire passing through said space and being looped over said first mentioned bent end portion, and having an end part bent about an end of said head to hold the head and said looped part of the free end from disengagement. 60

In witness whereof, I hereunto subscribe my name to this specification.

ALFRED L. ROEBUCK.
